UNITED STATES PATENT OFFICE.

VICTOR ABRAMS, OF CHICAGO, ILLINOIS, ASSIGNOR TO GIANT LADDER CO., OF CHICAGO,
ILLINOIS, A CORPORATION OF ILLINOIS.

SECTIONAL SCAFFOLD.

1,003,407.

Specification of Letters Patent. Patented Sept. 19, 1911.

Application filed December 3, 1909. Serial No. 531,279.

To all whom it may concern:

Be it known that I, VICTOR ABRAMS, citizen of the United States, residing at Chicago, in the county of Cook and State of Illinois, have invented certain new and useful Improvements in Sectional Scaffolds; and I do hereby declare the following to be a full, clear, and exact description of the invention, such as will enable others skilled in the art to which it appertains to make and use the same.

This invention relates to a novel construction in a sectional scaffold, the object being to provide a scaffold of this character which is very strong, durable and efficient and is easily erected and razed and which is safe, and consists in the features of construction and combinations of parts hereinafter fully described and claimed.

In the accompanying drawings illustrating this invention: Figure —1— is a perspective view of a scaffold constructed in accordance with my invention. Fig. —2— is an end elevation of the same. Fig. —3— is a fragmentary vertical sectional view of a scaffold constructed in accordance with my invention. Fig. —4— is a fragmentary end elevation of the same. Fig. —5— is a view similar to Fig. —1— showing the opposing ladders one of same being shown in side elevation. Fig. —6— is a fragmentary detail sectional view showing the joint between two super-imposed side rails of ladders comprising the uprights of the scaffold. Fig. —7— is a fragmentary detail section showing the lower end of one of the side rails of a ladder. Fig. —8— is a fragmentary detail plan view showing the fastening device employed for securing braces to rungs of the ladder sections. Fig. —9— is a fragmentary detail view in elevation showing one of the cross-pieces secured to the side rail of one of the ladders. Fig. —10— is a plan section on the line 10—10 of Fig. —9—. Fig. —11— is a sectional view on the line 11—11 of Fig. —9—. Fig. —12— is a plan section of the scaffold set up ready for use. Fig. —13— is a detail view in elevation of a locking device employed as a part of one of the fittings.

Sectional scaffolds made up of interfitting ladders in connection with braces connecting the same in parallel and maintaining them rigidly upright are quite commonly employed but in almost all instances the up-

per ladder sections are supported exclusively on the rungs of the lower ladder sections, the joints being effected in various ways.

In some instances the side rails of the upper ladder sections are supported directly upon the side rails of the lower sections so that the load is transferred continuously from the uppermost to the lowermost section through the side rails exclusively.

My said sectional scaffolding belongs to the last-named class, the improvements made by me relating more particularly to certain details of construction whereby the strength, rigidity and reliability of the scaffolding is greatly increased without increasing the weight or cost of construction of the same.

The said scaffolding is composed of a plurality of ladders of equal length and having preferably the same number of rungs spaced equi-distantly, the upper and lower rungs of each section being disposed exactly one-half the distance from the ends of the side rails as the distance between centers of adjacent rungs so that when one section is mounted upon the other the rungs at either side, that is above and below the joint, will be spaced exactly the same distance apart as the remaining rungs. This feature is, I believe, novel and constitutes an important feature of the invention.

The lower ends of the side rails 1 of each ladder are longitudinally slotted as at 2 and bound with a strap 3 of flat steel or other suitable metal suitably secured to the edges of said side rail. The upper ends of said side rails 1 are similarly bifurcated as at 4 and almost entirely surrounding and inclosing said upper end portion is a sleeve 5 of steel or the like which is substantially rectangular in plan section but is preferably slotted as at 6 on the inner face of the side rail, said sleeve being suitably secured to said side rail in any well-known manner. The free flanges 7 on either side of the slot 6 are preferably secured together by means of the cross-pieces 8 riveted thereto thereby preventing expansion of said sleeve.

The top and bottom rungs of the ladders extend into and are secured within the bifurcated end portions of said side rails 1 in any suitable manner. Pivoted secured to the upper end portion of one of the flanges 7 of the sleeve 5 is an inverted hook 9 which

is adapted to be sprung at its free end over a projection 10 on the opposite flange 7 of said sleeve to confine the rung 11 of an upper section and thus prevent separation 5 of a supported section from that upon which it is supported. The sections are thus securely locked together vertically.

The bifurcation of the upper and lower ends of the side rails 1 of the ladders serves 10 to prevent the same when swelling under the influence of moisture exerting a sufficient pressure on the sleeve 5 or strap 3 to vary the size of the interfitting parts and thereby prevent or render more difficult the proper 15 assembling of the ladders to form a scaffold.

In building the scaffold the ladders are preferably set up to constitute the four corners of a square, the side rails and rungs thereof being maintained parallel with each 20 other. The corner uprights thus constituted are secured together by means of knee braces 13 and cross-pieces 14, the former being equipped at the free ends of their component members with suitable devices for firmly engaging the rungs of opposed ladders, while the latter are provided with devices for engaging the side rails 1 of the ladders and also the rungs thereof as is hereinafter further explained in detail as 25 follows: The knee braces 13 comprise each a horizontal bar 12 equipped on its lower edge and at both ends with a locking device consisting of a casting 15 provided in its lower face with a recess 16 to receive a rung 30 of a ladder. The said casting 15 is preferably stepped and is provided with threaded openings through which the threaded ends of the bolts 17 pass to secure said casting to said bar. The free ends of the bolts pass 35 through longitudinal slots in the flanges of a Z-shaped member 18, the latter being held in place by means of the nut 19 and butterfly or thumb nut 20. The said Z-shaped member 18 may be moved longitudinally so that 40 one end of the same covers the recess 16, as shown in Figs. —1— and —3—, and may be moved rearwardly a distance sufficient to undercover said recess to permit a rung to be withdrawn from the same. The braces 45 21 are similarly equipped with said locking devices but the latter are mounted on the upper edge of said braces 21 instead of the lower so that after mounting the bar 12 in position the said braces 21 may be swung 50 upwardly so as to throw the said locking devices into engagement with the rungs of the ladder sections.

The cross or X-braces consist of oppositely inclined bars disposed between opposing side rails of adjacent ladders and each thereof is equipped at its ends with an engaging device which consists of a J-shaped member 22 provided with a flange 23 resting against a side face of the bar to which 55 it is secured. The said member 22 is pro-

vided in its free flange with a slot 24 in which a rung of the ladder is received. A Z-shaped member 25 is secured through one of its flanges to the opposite face of the bar and a single bolt 26 serves to secure the 60 members 22 and 25 pivotally to said bar, said bolt being equipped with the thumb nut 27 to more firmly secure said members thereon. The free flange of the member 25 is provided at its free end with a projection 75 28 entering the mouth of the slot 24 in the member 22 thereby preventing rotation of said member 25 when said thumb nut 27 is drawn up to secure said members firmly in position. The engagement of the rung with the walls of the slot 24 in the member 22 will obviously prevent longitudinal movement of said member 22 on the side rail so that said bars or cross braces are thus firmly secured and serve to prevent relative 80 lateral and longitudinal movement of the ladder sections secured together thereby. If it is desired the said cross braces may be arranged in pairs pivotally secured together between their ends but owing to their relatively great length and consequent difficulty of handling it is more advisable and convenient to maintain said bars separate from each other.

In erecting a scaffold by means of the 85 sectional ladders it is primarily necessary that the lowermost or base sections shall be supported at a uniform level or at different levels corresponding in variations in elevation by the distance between centers of the 90 rungs of the sections or twice, three times, etc., the last-named distance, it being essential that those rungs of all ladders to which the knee braces 13 are to be secured shall be disposed in the same horizontal plane so 95 that flooring supported on the bars 14 or scaffolds 29 of greater width and strength corresponding in shape with said knee braces shall be level. After having set up two pairs of ladders each of which is secured together by means of the knee braces 13, the said pairs are connected together 100 by means of the diagonal braces 14 secured at opposite ends to opposing side rails of opposed ladders at different elevations. A 105 rectangular structure is thus formed which may be extended upwardly to any desired height with ease and rapidity and which may be extended laterally in all directions 110 to cover any desired area. The side rails 115 of all upper ladder sections rest directly upon the side rails of the next lower sections to which they are locked by means of the hooks and also, if desired, by so disposing the knee braces that the horizontal bars 120 thereof engage the rungs of upper sections while the pivoted legs thereof engage the rungs of the supporting sections. The said knee braces 13, cross-braces 14 and scaffolds 29 serve to maintain all uprights rigidly in 125 130

vertical position and prevent any deflection thereof. The scaffolds 29 may be described as comprising a pair of knee pieces disposed parallel with each other and the several opposed parts of which are secured together by means of rungs of less length than the rungs of the ladders.

5 Flooring may be supported on the scaffolds 29 at any desired elevation and said scaffolds may be disposed at several different elevations in the scaffold so as to permit several gangs of men to work at different elevations as in painting and decorating walls of halls, churches, theaters, etc., thus 10 enabling lathing, plastering and decoration of walls and ceiling to be carried on simultaneously.

I claim as my invention:

1. Sectional ladders each equipped at one 20 end of each of its side rails with sleeves embracing and secured to the same and projecting beyond the ends thereof, U-shaped straps embracing and secured to the other ends of the side rails of said ladders, said 25 projecting end portions of said sleeves adapted to receive the bound end portions of companion ladders to join the same, both

ends of said side rails being longitudinally slotted to permit swelling thereof without exerting undue pressure on the members embracing the same.

2. Sectional ladders having rungs spaced equi-distantly from each other, the end rungs of each ladder spaced one-half the distance from the adjacent ends of the side 30 rails as the distance between adjacent rungs, sleeves embracing and secured to one end of each of the side rails of said ladders and projecting beyond the ends thereof, said sleeves adapted to receive the other ends of 35 the side rails of companion ladders to join the same, there being slots in the opposed walls of the sleeves of each ladder adapted to receive a rung of the companion ladder, and latches spanning said slots and operatively 40 engaging said rung to hold said ladders against separation.

In testimony whereof I have signed my name in presence of two subscribing witnesses.

VICTOR ABRAMS.
